UNITED STATES PATENT OFFICE.

JAMES CLAYTON, OF SEBAKWE, BABBACOMBE, ENGLAND, ASSIGNOR TO THE VISCOSE COMPANY, OF MARCUS HOOK, PENNSYLVANIA, A CORPORATION OF PENNSYLVANIA.

SPINNING BOX FOR ARTIFICIAL SILK.

1,417,456.

Specification of Letters Patent. Patented May 23, 1922.

Application filed November 11, 1920. Serial No. 423,316.

To all whom it may concern:

Be it known that I, JAMES CLAYTON, a subject of the King of Great Britain and Ireland, and a resident of Sebakwe, Babba-combe, county of Devon, England, and having a post-office address at Sebakwe, Babba-combe, county of Devon, England, have invented certain new and useful Improvements in Spinning Boxes for Artificial Silk, of which the following is a specification.

My invention relates to apparatus for spinning artificial silk, and particularly to the spinning box. The object of the present invention is to provide a rotary box support of improved construction, which may be used to advantage with a box of the type shown in my application of even date herewith, although it is to be understood that the present support may be used with any other type of box for which it is adapted.

In the accompanying drawings—

Fig. 1 is a side elevation partially in section through a rotary box support in which my invention is embodied in one form; and Figs. 2 and 3 are sections illustrating the method of securing the face plate in the body of the support.

In my prior application Serial No. 227,348, filed April 8, 1918, I have described a spinning box which comprises a basket like body or cover fitting upon a rotary support or base and held thereto by centrifugally operated means. The present invention relates particularly to the rotary base or support on which the box proper is mounted, and presents certain features of improvement.

The base 5 may be formed in any suitable manner, preferably by casting, and comprises a hub 6 provided with a cone bushing 7, into which is driven the taper end 8 of the rotary spinning spindle 9. The coned peripheral flange 10 of the base is channeled at 11 to receive a ring 12 of soft rubber or the like. Below this channel is a shoulder 14, upon which rests the lower edge of the spinning box proper 13 of any suitable construction, the side wall of which sleeves upon the base and embraces the ring 12.

When the apparatus is in operation, the 50 spindle 9 is very rapidly rotated. This causes the elastic rubber ring 12 to expand under centrifugal force, and it engages and retains the box 13 with a velvet grip. As soon as the spindle is halted, the ring 12 contracts by reason of its inherent elasticity and releases its grip on the box so that the latter may be freely lifted to remove the spun fiber cake.

To prevent discoloration of the cellulose 60 fiber by contact with the metal body of the base 5 in the presence of the acids carried into the box by the filaments, I provide a facing plate 15 which completely overlies the base. To secure this in position the periphery of the plate is undercut at 16, while the base 5 is provided with a marginal flange 17 which, after the lining plate is placed in position, is pressed into the undercut 16 and holds the plate rigidly in assembled position.

Various modifications will readily occur to those dealing with the problem, which do not depart from what I claim as my invention.

I claim—

1. In apparatus for spinning artificial silk, a rotary base for a spinning box, said base having a peripheral channel, and an expansible rubber ring lying in said channel 80 and adapted to expand under centrifugal action into gripping engagement with the wall of a box sleeving upon said base, substantially as subscribed.

2. In apparatus for spinning artificial 85 silk, a rotary support for a spinning box, said support comprising a base having an up-standing marginal flange, and a facing plate overlying said base and flange and peripherally undercut to receive and be 90 gripped by said flange, substantially as described.

In testimony whereof I have signed my name to this specification.

JAMES CLAYTON.
